CONDUIT CONNECTOR FOR AGITATING
DEVICES

Lowe E. Simpson, Cincinnati, Ohio

Application January 29, 1934, Serial No. 708,737

3 Claims. (Cl. 209—240)

My invention relates to devices in the form of sleeves which are employed to connect conduit pipes extending to and from devices to which gases, liquids, or solids are being conveyed, or 5 from which they are being discharged, to mechanisms which are agitated to perform work on the material being conveyed.

The immediate use for which my invention has been applied is that of conveying material to and 10 from sorting and separating screens. Although not a sufficiently embracing term, the machines using such screens are sometimes called sifters, and include an enclosed body in which the screens are located, with orifices leading to and 15 away from the screen or screens.

It has been the practice in the past to attach a beaded edge ring to the several orifices leading to and from sifting machines and provide the customer with a beaded ring to attach to the 20 several pipes, hopper mouths or conduits which are employed in handling the material to be treated to and from the device. The customer then has in the past placed a flannel sleeve or 25 open-ended bag over the rings and employed these bags as connectors.

These bags are not satisfactory. Their life is not long, and they are not dust-tight; when 30 handling liquids they leak and deteriorate rapidly, they are unsightly and often sag, thus constricting flow. When used with exhaust systems to withdraw dust, these bags collapse and thus restrict flow.

However, these bags do function to permit of 35 a regular predetermined movement of the sifting machine at one end, while the other end is held in fixed position.

It is the object of my invention to provide a 40 suitable connector sleeve which will remain in its original form without distortion, will convey liquids, gases, and dust without any leakage, will be long lasting, will not collapse either because of sagging of its own weight or become slack for any reason, or because of pressure from without due to being used with an exhaust fan for dust 45 or gas. At the same time, it is my object to provide a structure which will permit of the regular movement of the sifting devices to which they are attached at one end, while the end connected to the in or out pipes remains fixed.

50 A connector sleeve which is formed of relatively stiff flexible material, with considerable resiliency, such as a good grade of rubber, and which has corrugations around it, either annular or perhaps spiral, I have found to serve my purpose admirably. The connector will extend length-

wise and contract again when used with a machine which has an up and down motion, and will accommodate, to a certain degree, discrepancies in required distance from delivery spout to inlet hole in sifting machines, and discrepancies in 5 exact alignment of the delivery spout and inlet hole. The sleeve or connector will lend itself to entire endwise flexing, and to unequal flexing as between opposite sides. It never will become 10 tight in a lengthwise direction between connections, and is not subject to whipping action which will tear it away from the connections at either point of connection. However, the connector will not collapse or become kinked at any time, thus 15 shutting down or limiting the flow of material therethrough.

It is my further object to provide my new connector with a quick detachable but secure mounting on the beaded rings of the type now in use.

While in the drawings I show only applications 20 of my invention to sifting machines, it should be noted that it will have application to other uses, such as, for example, to a barrel filling machine in which the barrel is set on an agitating platform to jar down the material as it passes into 25 the barrel, and in which the barrel is equipped, when being filled, with a cover plate, the orifice in which is provided with one of the beaded rings.

The features of novelty of my invention will be 30 stated in the appended claims to which reference is hereby made.

In the drawings:

Figure 1 is a central vertical section through the new connector.

Figure 2 is a like section through a beaded ring. 35

Figure 3 is an elevation, partly in section, showing the use of the new device in a sifter.

Figure 4 is a longitudinal section of another type of sifting or sorting machine.

Figure 5 is a detail section of a modified form 40 of connector.

Figure 6 is a detail section showing the type of connector ring used with this modified connector.

Referring first generally to the sifter which I 45 have used as an illustration of the employment of my invention, I show a frame 1, a mechanism 2 for causing it to move about in a suitable path for setting up agitation of material, a housing 3, surrounding the screen 4, and orifices 5 and 6, one 50 being an inlet and two outlets.

The orifices are equipped with rings 7, which have beads 7a rolled into their outer ends. It 55 will be obvious without illustration, that a double beaded plain ring could be used as an adapter

between two of my connector sleeves. It will also be understood that the conduits, hopper mouths, or container spouts, or what not, from which material flows, or out through which it flows, will 5 be equipped with rings 7 having beaded edges 7a.

The connector consists of a sleeve 8 of gum rubber or analogous material, so far as properties are concerned; and because I refer to rubber in the remainder of this specification and in the 10 claims, I do not wish to be understood as excluding synthetic materials and like elastic, wear-resistant material, from being equivalent.

The sleeve 8 is corrugated with corrugations 9. These impart stiffness against collapse, ballooning and sagging, and promote the resistance to 15 wear of the sleeve upon the repeated bendings to which it must be subjected.

The corrugations also provide seats for distending rings 10, which may sometimes be required 20 in case a very heavy exhaust vacuum is maintained within the sleeve.

Each end of the sleeve is preferably provided 25 with a flange 11 for manipulation and strengthening purposes, and above the flange on the inside with a groove 12, for engaging over the bead 7a of one of the beaded orifice rings. As illustrated, the sleeves connect an inlet conduit 13 to the sifter, and outlet pipes 14 to the sifter.

In use the connector sleeve can readily be set 30 up and dismounted by merely snapping the ends of the connector over the ring beads, and bending the ends away so as to snap them away from the beads. When seated over the beaded rings, the connector is very firmly held against lengthwise removal.

In Figure 4 I have shown a sifting machine with a body 15, which is caused to travel at one 35 end in a path which is in a vertical circular arc, under actuation of the eccentric 16. The connector sleeves are here of a modified type, as shown in Figures 4 and 5. The bodies are the same as shown at 17, except that there are fewer 40 corrugations. The connector rings 18, instead of having beads thereon, have grooves 19 for receiving the ends of the connector sleeves. The connector sleeves have internal beads 20 for engaging the grooves in the connector rings. Flanges 21 on the sleeve ends serve as finger holes 45 for manipulating the sleeves. This is an inversion of the groove and bead relationship already described. Both structures operate in the same way.

During the operation of the sifter, the end 50 of the sleeve connected to the sifter will readily move to and fro, following the sifter movement, while the other end will remain still, due to being connected to a non-moving part.

As heretofore stated, I have illustrated but one

of the analogous uses to which my invention can be put.

Having thus described my invention, what I claim as new and desire to secure by Letters Patent, is:—

1. The combination with a shaking member for treating a substance, same having a feed orifice, and a fixed conduit to be connected thereto, of a connector sleeve comprising a tubular rubber body having corrugations circumferentially thereof, and a connector ring arranged to fit within the body and fixedly secured about the said orifice, the tubular body and the ring, one of them having an annular bead, and the other a groove adapted to fit over the bead when the body 15 is set over the ring, the end of the tubular body where it is attached to the ring, having a radially projecting flange for manipulating the tubular body, and means for detachably connecting said tubular body portion to the end of the 20 conduit, for the purpose described.

2. The combination with a shaking member for treating a substance, same having a feed orifice, and a fixed conduit to be connected thereto, of a connector sleeve comprising a tubular rubber body having corrugations circumferentially 25 thereof, and a connector ring arranged to fit within the body and fixedly secured about the said orifice, the tubular body and the ring, one of them having an annular bead, and the other a groove adapted to fit over the bead when the body 30 is set over the ring, the end of the tubular body where it is attached to the ring, having a radially projecting flange for manipulating the tubular body, and means for detachably connecting said tubular body portion to the end of the 35 conduit, for the purpose described.

3. The combination with a shaking member for treating a substance, same having a feed orifice, and a fixed conduit to be connected thereto, of a connector sleeve comprising a tubular rubber body having corrugations circumferentially 45 thereof, and a connector ring arranged to fit within the body and fixedly secured about the said orifice, the tubular body and the ring, one of them having an annular bead, and the other a groove adapted to fit over the bead when the body 50 is set over the ring, the end of the tubular body where it is attached to the ring, having a radially projecting flange for manipulating the tubular body, and means for detachably connecting said tubular body portion to the end of the 55 conduit, for the purpose described.

LOWE E. SIMPSON.
